STAND-OFF INSULATOR

Maurice G. Knoy, Lafayette, Ind., assignor to Rostone Corporation, Lafayette, Ind., a corporation of Indiana

Filed Sept. 27, 1963, Ser. No. 76,759

Term of patent 14 years

(Cl. D26—10)

FIG. 1.

FIG. 2.

FIG. 3.

FIG. 1 is a perspective view of a stand-off insulator showing my design;

FIG. 2 is a side elevation of the insulator shown in FIG. 1; and

FIG. 3 is an end elevation of the insulator shown in FIG. 1.

I claim:

The ornamental design for a stand-off insulator, substantially as shown.
